UNITED STATES PATENT OFFICE.

HARVEY F. MARANVILLE, OF AKRON, OHIO, ASSIGNOR TO THE PERFECTION SPRING COMPANY, OF CLEVELAND, OHIO, A CORPORATION OF OHIO.

LUBRICATING SYSTEM.

1,071,623.

Specification of Letters Patent. Patented Aug. 26, 1913.

Application filed February 24, 1910. Serial No. 545,742.

To all whom it may concern:

Be it known that I, HARVEY F. MARANVILLE, a citizen of the United States, residing at Akron, in the county of Summit and State of Ohio, have invented a certain new and useful Improvement in Lubricating Systems, of which the following is a full, clear, and exact description, reference being had to the accompanying drawings.

10 This invention relates to systems for lubricating machinery and, in the particular embodiment shown herein, is designed with special reference to automobiles.

The apparatus disclosed herein constitutes a system by means of which the various parts of the engine of an automobile may be conveniently lubricated, a predetermined level of oil may be maintained in the engine base or crank case, sediment may 20 be automatically and conveniently removed from such base, and the surplus oil flowing from the engine and from such base may be effectively filtered, washed and cooled, at the same time providing an arrangement 25 whereby the quantity of oil in the reservoir or tank may be conveniently and accurately indicated.

The object of the invention is to realize the above operations and results in an efficient and economical manner; also to provide a particularly compact apparatus for this purpose which, as to certain features of construction is especially adapted for application to automobiles.

35 Still further and generally speaking, the invention may be defined as consisting of the combinations of elements and parts embodied in the claims hereto annexed and illustrated in the drawings forming part hereof, 40 wherein—

Figure 1 represents a side elevation of a multi-cylinder engine having my invention applied thereto; Fig. 2 represents a vertical sectional view taken through the lower portion of a cylinder and crank case or base of an engine showing a part of my invention applied thereto; Fig. 3 represents a horizontal sectional view taken through the upper portion of the engine base, below the 50 cover for the receptacle projecting from said base.

Describing the parts with reference to the drawings, wherein the same numerals designate like parts in the different views, 1 rep-

resents the hood of an automobile and 2 the front wheel thereof. Beneath the hood and supported by the frame in the ordinary manner is the engine, shown herein as of the four-cylinder type, the cylinders being designated by the numeral 3. The cylinders 60 are supported by a base comprising an upper casting or member 4 and a lower casting or member 5. The upper member may be of ordinary type and is shown as provided with flanges 6 to which the lower member 65 may be secured by means of corresponding flanges 7 and bolts 8, the two members forming a crank case. Each cylinder is provided with a piston 9 of any standard construction, a piston of the trunk type being shown. 70 A connecting rod 10 extends between the piston and the crank 11, being connected to the latter in any approved manner.

The lower section or member 5 is provided at its lowest point with a preferably 75 elongated opening 12 communicating with a chamber 13 formed in a receptacle attached to the lower base section of the engine. The bottom 14, end 15, and sides 16 of this receptacle may be conveniently cast 80 with the bottom section 5, the receptacle being provided with a removable cover 17, which is shown as provided at its inner edge with an upwardly projecting flange 18 by means of which it may be fastened to the 85 engine base, as by screws 19.

The space within the receptacle 13 is divided into two or more compartments (two being shown) by means of a vertical partition 20 extending upwardly from the 90 bottom plate 14 and having at its upper end a downwardly extending baffle plate 21. This partition divides the receptacle into two chambers 22 and 23. The chamber 22 communicates with the lower portion of the 95 engine base or crank case by means of the elongated openings 12. The bottom of the receptacle 13 is conveniently cast with the bottom section 5, as stated, and is located below the same, being connected with the casting by means of a short vertical wall 24 which extends downwardly from the lowest portion of the discharge slots 12. Each slot 12 is bounded on one side by the junction of the wall 24 with the lowest part of the lower 100 section 5, the opposite side of the slot being formed by deflecting upwardly the portion of the lower section which is opposite such 105

junction, as shown at 25, whereby each slot possesses considerable vertical, as well as longitudinal, extent. Each slot 12 is so arranged as to be beneath a crank pin 11 and is preferably co-extensive in length with the length of such crank pin. Each of these slots extends laterally from the center or lowest portion of the bottom section of the engine base or crank case in the same direction in which the crank and connecting rod revolve when the engine is going "ahead", as indicated by the arrow on Fig. 2.

Partition members 5^a divide the space within the receptacle 5 into a plurality of compartments, the partitions extending above the cranks when the latter are in their lowermost positions, whereby oil may be maintained in contact with each crank when the engine is tipped, as when, for instance, the motor vehicle to which the engine is attached is ascending or descending a hill.

The outer wall 15 of the receptacle 13 is provided with a filling tube 26, the upper end of which is substantially on a level with 25 the top of the partition 20.

The compartment 22 is provided with a clean out opening closed by a plug 22^a. Through this opening the collected dirt may be readily removed from the chamber.

30 The compartment 23 is provided at its lower end with a pipe 27 extending to a pump 28, which may be of any convenient type, being shown as rotary pump in Fig. 1 of the drawings.

35 The pump shaft 29 is shown as driven by means of a gear 30 meshing with a gear 31 on the engine shaft 32. Other driving means may be used for the pump if desired. The outlet from the pump is connected by 40 means of a pipe 33 with the casing 34 of my combined filtering, washing, cooling and storage tank. This pipe is conveniently threaded into the removable cover 35 of said tank. The tank is provided with an outlet 45 pipe 36 conducting filtered oil to a manifold 37, from which manifold pipes 38 extend to the upper portion of the engine base or crank case. The lower end 39 of each of the pipes 38 projects through the 50 wall of the upper section 4 of the crank case and is preferably reduced in diameter so as to discharge oil in a fine stream or jet upon the connecting rod journal as the rod revolves with the crank pin in the crank 55 casing.

40 denotes a gage which is connected by a suitable pipe 41 with the casing 34 to indicate the level of the filtered oil in said casing.

The chamber for filtered oil in the casing 60 34 is of the same capacity as the chamber 23 in the receptacle 13.

The details of construction of the filtering tank are shown, described and claimed in my application No. 569,459, filed June 29th, 65 1910, which is a division of this application.

With the parts arranged as above described, the operation is as follows:—Oil is supplied from the filtering and cooling tank manifold 37 and pipes 38 into the engine base or crank casing. This oil is so directed as to 70 strike the connecting rod journals and oil the parts. Oil accumulates in the lower portion of the engine base or crank casing until it reaches the level maintained by the top of the partition 20. It there overflows 75 into the chamber 23, whence it is pumped by the pump 28 and the pipe 33 into the filtering, washing and cooling tank.

Carbon and other sediment accumulate in the bottom of the crank case. Owing to 80 the location and arrangement of the slotted ports or apertures 12 in the sediment chamber 22, the sediment is swept out of the crank case by the revolution of the cranks and carried into the chamber 22, whence it 85 may be conveniently removed by taking off the cover 17. The baffle 21 prevents the sediment from being carried over the partition 20 and into the chamber 23.

Among the objects of my invention are 90 the constant supply of clean, cool oil in ample quantity to the places where needed; the positive removal of the sediment from the oil in the crank case through the operation of the machinery itself; the ability to 95 observe at all times the condition of the oil in the system; and the ability to replenish the oil, as exhausted, by means of the filling tube 26. A further and marked advantage in the automobile art is the adaptability of 100 my system for all incidents of use. The substitution of the lower section of the ordinary crank case or engine base by the corresponding parts of my invention can be made conveniently and at comparatively 105 small expense, while the distance usually provided between the engine base and the side frames of automobiles is amply sufficient to accommodate the receivable containing the sediment and filling chambers.

In practice the outlet pipe 36 is of less capacity than the pipe 33, a convenient size for these pipes being $\frac{1}{2}$ inch for the pipe 33, and $\frac{3}{8}$ inch for the pipe 36.

Furthermore, the construction of the attachment to the engine base insures, at all times that the gage 40 shows the maintenance of oil at the proper level in the engine base for lubricating purposes.

In the specification and claims, reference 120 is made to the crank dipping into the oil in the crank case in order to lubricate by the splash system and sweep the sediment from the case into the chamber provided for the sediment. By the term "crank" I do not propose to be limited to any special part of the crank shaft or the co-operating portions of the connecting rod, it being sufficient for the purpose of my invention that any of the parts rotating with the crank shaft dip into 125 130

the oil and sweep out the sediment as described.

Having thus described my invention, what I claim is:

5 1. The combination of a crank case, a crank shaft having a crank in said case, said case having an aperture in its bottom below said crank, a sediment receptacle communicating with said aperture and carried by the 10 case, and means in said receptacle for maintaining a level of oil in the case above said aperture to permit the crank to dip therein and sweep sediment through said aperture.

15 2. In a lubricating system, the combination with a multi-cylinder engine, of a shaft having a plurality of cranks for said engine, a case for said cranks, a receptacle, apertures communicating with the lower portion of said case and with said receptacle and arranged to receive the sediment moved by the 20 action of said cranks, means in said receptacle for maintaining a level of oil in said case above said apertures, a filtering and cooling apparatus, a pump connecting said 25 apparatus with said receptacle and connections for supplying oil from said apparatus to said engine.

30 3. The combination, with a crank case having a crank shaft therein provided with a crank, said case having in its bottom an elongated aperture below said crank, of a receptacle carried by said case and communicating with said case through said aperture, said receptacle being provided with a 35 partition adapted to maintain a level of oil in the case above said aperture and having a chamber located externally with respect to said partition, and means for supplying oil from said chamber to the crank case.

40 4. The combination, with a crank case having a crank shaft therein provided with a crank, said case having in its bottom an elongated aperture below said crank, of a receptacle communicating with said case 45 through said opening, said receptacle being provided with a partition adapted to maintain a level of oil in the case above said aperture and having a chamber located externally with respect to said partition, said 50 partition being provided with a baffle preventing the sediment from being carried over into such external chamber.

55 5. The combination, with an engine and a crank case having an aperture in the lower portion thereof, of a receptacle communicating with said aperture and having a vertically extending partition adapted to maintain a level of oil within the case, said receptacle being provided with a chamber located 60 externally of said partition, a storage receptacle located above the former receptacle, a pump for supplying oil from the chamber to the storage receptacle, the latter receptacle and said chamber being of substantially the same capacity, a connection 65

between the storage receptacle and the engine and a gage carried by the storage receptacle.

6. The combination, with an engine and a crank case having an aperture in the lower portion thereof, of a receptacle communicating with said aperture and adapted to maintain a level of oil within the case above said aperture, said receptacle being provided with a chamber located exteriorly of said partition, a storage receptacle, means for supplying oil from the former receptacle to the latter receptacle, the receptacles being of substantially the same capacity, a connection between the storage receptacle and the engine, and a gage carried by the storage receptacle. 70 75

7. The combination of a crank case having an aperture formed in the lower portion thereof, one side wall of said aperture being at the lowest part of said case and the opposite side wall being above the former wall and deflected inwardly and upwardly, said aperture being located below the travel of the crank in said case, and a receptacle communicating with the case through said aperture and having a wall extending above said aperture. 80 85

8. In a lubricating system, the combination of an engine having a crank case having in its bottom one or more elongated ports for the discharge of sediment, a receptacle carried by said case and communicating therewith through such port or ports, means for maintaining oil in said case above the bottom thereof, means in said receptacle for separating the sediment from the oil flowing thereto from the base, a filtering device, a pump for forcing oil from the receptacle into the latter device, a pipe connecting said pump and said device, a pipe of smaller capacity than the first-mentioned pipe extending from the filtering device, and branch pipes extending from the latter pipe to the engine. 90 95 100 105

9. The combination, with a crank case having an aperture in the lower part thereof, of a receptacle communicating with said case through said aperture, a partition in said receptacle extending above said aperture and adapted to maintain a level of oil within the case and providing a pair of chambers in said receptacle, a filling tube communicating with the chamber provided exteriorly of said partition and extending upwardly no higher than said partition, and means for supplying oil from the latter chamber to said case. 110 115 120

10. The combination, with an engine, of a crank case having an aperture in the lower part thereof, a receptacle communicating with said case through said aperture, a partition in said receptacle extending above said aperture and adapted to maintain a level of oil within the case and providing a pair of chambers in said receptacle, a filling tube 125 130

communicating with the chamber provided exteriorly of said partition and extending no higher than said partition, a filter, means for supplying oil from the latter chamber to 5 said filter, and means for supplying oil from the filter to the crank case.

11. The combination, with a crank case, said case being provided with a port in the bottom thereof, of a sediment receptacle 10 communicating with said port, a second receptacle communicating with the sediment receptacle, means for maintaining a level of oil in the case extending above said port, and connections for supplying oil from the second receptacle to the crank case.

12. The combination of a crank case, a crank shaft having a crank in said case, said case having an aperture in its bottom below said crank, a sediment receptacle communicating with said aperture, and an overflow chamber adapted to receive oil from the crank case and to maintain a level of oil in said case above said aperture at a height to insure the dipping of the crank into the oil 25 to permit the crank to sweep sediment through said aperture into the sediment receptacle.

13. The combination of a crank case, a crank shaft having a crank in said case, said case having an aperture in its bottom below said crank, that side of the aperture toward which the crank turns when the engine is going ahead being higher than the other, a sediment receptacle communicating with 30 said aperture, and means whereby a level of oil may be maintained in the crank case above said aperture and at a height to insure the dipping of the crank into the oil to sweep the sediment toward and through said 35 aperture.

14. The combination of a crank case, a crank shaft within said case having a crank therein, said case being provided with an aperture in the bottom thereof below said 45 crank, and a sediment receptacle communicating with said case through said aperture and having a wall extending above said

aperture to a height to maintain a level of oil in the case into which the crank may dip.

15. The combination, with a multi-cylinder engine, of a shaft, cranks on said shaft, one for each cylinder of the engine, a case for the shaft and inclosing the cranks thereof, said case having transverse partitions located between the cranks and forming compartments, each compartment being provided with a port in the lower part thereof, a sediment receptacle communicating with each compartment through its port, and means whereby a level of oil may be maintained in each compartment above its port and at a height to insure the crank dipping thereinto.

16. The combination of a crank shaft having a crank, a crank case for said crank shaft and crank and comprising an upper section and a lower section detachably secured to the upper section, a receptacle carried by the lower section and having a filling connection and including means for maintaining a level of oil in the crank case at a height to insure the dipping of the crank thereinto and a sediment receptacle communicating by a port with the lowest point of such lower section.

17. The combination of a crank case, a crank shaft having a crank in said case, said crank case having an aperture in its bottom below the crank shaft through which aperture sediment may pass, a receptacle communicating with the crank case in such manner as to maintain within such case a level of oil above the aperture and at a height to insure the dipping of a portion of the crank thereinto, a filtering device, a pump for supplying oil from the receptacle to said device, and an oil supply leading from the filtering device.

In testimony whereof, I hereunto affix my signature in the presence of two witnesses.

HARVEY F. MARANVILLE.
